UNITED STATES PATENT OFFICE

2,668,081

WATER SHIELD

Jack C. Kanter, Norfolk, Va.

Application August 3, 1951, Serial No. 240,136

4 Claims. (Cl. 299—69)

1

The present invention relates to fire prevention apparatus which is characterized by having structure associated therewith for effecting a water curtain between the object desired to be protected and a fire.

More particularly, the instant invention includes apparatus which may be connected to a source of fire extinguishing fluid such, for example, as water under pressure and may be positioned upon the roof or other portion of such a structure, or in a suitable position adjacent the structure.

Heretofore, difficulty has been experienced in the construction and operation of such fire preventive equipment. One reason for such difficulty in the prior art devices is that no means is provided therein for rendering the device capable of being temporarily secured to a portion of a building or similar structure for the purpose of protecting such structure from the spreading of an adjacent fire. Consequently, the prior art devices require several firemen to hold them in their desired positions and thereby prevent the performance of other equally important duties by these men. In addition, the safety of the men in control of such prior art apparatus is frequently endangered by falling debris and explosions occurring within the burning structure. Furthermore, as utilized in practice, these prior art devices are intended for the purpose of fighting fires and it has not been contemplated in the construction of such devices to provide a suitable apparatus for the prevention of the spreading of fires. Another disadvantage of the prior art devices is that the streams of water are ejected from the rotating nozzles thereof at large angles relative to the vertical center line of the nozzle, thereby creating a waste of water and the probability of extensive water damage to the structure within which the device is used.

It has been found, in addition to the aforementioned disadvantages of the prior art devices, that firemen are reluctant to attend the nozzles associated therewith during cold weather for the reason that the backward streams of water which face the operators of the nozzle frequently produce frozen hands and faces.

In contradistinction to the foregoing disadvantages of the prior art devices, the apparatus of the instant invention can be carried by one man to its desired position, clamped in place, attached to a line of fire hose, and left completely unattended.

Accordingly, one of the objects of the present invention resides in the provision of apparatus

5

for producing a protective water curtain in front of and along the surface of a wall, tank, or other object exposed to the heat of a fire in an adjacent structure.

Another object of the present invention is to provide a novel and useful apparatus which may be clamped or placed on a piece of fire-fighting equipment for the purpose of preventing a fire from "jumping" across a street or alley.

Another object of the present invention is the provision of a new and improved apparatus which will produce a water curtain behind which firemen can safely conduct fire-fighting operations.

Another object is the provision of a fire preventive apparatus which efficiently provides a circular water curtain to thereby adequately protect a structure upwardly, downwardly, and sideways from the heat of a fire in an adjacent structure.

Other objects and many of the attendant advantages of this invention will be readily appreciated when the same becomes better understood by reference to the following detailed description when considered in connection with the accompanying drawings, wherein:

Figure 1 is a side elevational view in accordance with one embodiment of the apparatus of the instant invention;

Figure 2 is a top plan view of the apparatus shown in Figure 1;

Figure 3 is an end elevational view of the apparatus as viewed from the hose connection end thereof;

Figure 4 is an end elevational view of the present invention as viewed from the rotating nozzle end thereof;

Figure 5 is a side elevational view of the nozzle end of the present invention partly shown in section as viewed from section line 5—5 in Figure 2;

Figure 6 is a vertical sectional view of the hose connection end of the present invention and which is taken on section line 6—6 in Figure 2;

Figure 7 is a vertical sectional view of my invention as viewed from section line 7—7 in Figure 2;

Figure 8 is a side elevation view in accordance with another embodiment of the apparatus of the present invention;

Figure 9 is a top plan view of the apparatus of Figure 8 with the hose line disconnected therefrom; and

Figure 10 is an end elevation view of the apparatus of Figure 8 as viewed from the nozzle end thereof.

Referring now to the accompanying drawings

2

in which like reference numerals are employed to designate like parts and, more particularly, to Figure 1 thereof, in which reference numeral 11 designates a tubular supporting member having the general configuration of a C clamp, it will be observed that this supporting member is provided with a valve 12 of any conventional type found suitable for the purpose. A threaded connector portion 13 is employed for the purpose of connecting the apparatus by hose H to a source of water under pressure.

Two legs 14 and 15 of the C clamp supporting member are tubular, thereby providing fluid communication between the threaded connector 13 and a rotatably mounted nozzle 16.

As best indicated in Figures 4 and 5, the cylindrical nozzle 16 is provided with a plurality of circumferentially spaced discharge outlets or orifices 17 directed so as to produce a rotary motion of the nozzle. In addition, certain ones of orifices 17 are offset in opposite directions from the vertical center line or diameter 18 of the nozzle at a small angle which may vary from 0° to about 10°, depending upon the results desired. It has been found that angles in excess of 10° produce undesirable results for the reason that such large angles of water projection result in substantial water damage in structures otherwise undamaged. Certain other ones of orifices 17 are positioned on the vertical center line 18.

In both embodiments of the present invention as herein disclosed, the orifices 17 may be considered in groups of three. It will be readily apparent from an inspection of Figures 4 and 5 that the first orifice of each group such, for example, as orifice 19, is positioned so as to project water outwardly from the device and slightly to the right thereof, as viewed in Figure 5. The second orifice 20 of each group is positioned to project water outwardly in a plane containing the vertical center line 18 of the nozzle and normal to the horizontal center line 21 thereof. The third orifice 22 of each group is positioned to project water outwardly from the nozzle and slightly to the left of the vertical center line 18, as best indicated in Figure 5. The size of these apertures may vary, but it has been determined experimentally that the apertures should have an inside diameter lying within the range of one-fourth inch to five-eighths inch for optimum results.

The C clamp supporting bracket is further provided with a clamping flange 23 having an internally threaded hole 24, therein for the accommodation of a threaded clamping screw 25. A stop flange 26 extends inwardly of leg 15 and is in alignment with the clamping screw 25 and the flange 23. An internally threaded hole 27 is provided in the stop flange 26 for accommodating bolt 28 which is provided for the purpose of extending the length of stop flange 26 should it be found desirable to do so. Pivotaly mounted bars 29 and 30, which are pointed at the outer end thereof, are provided for the purpose of contributing support to the C clamp when secured to the wall 31 of a building and, in addition, to provide a means for positioning the device upon a roof 32 of a building or similar structure. When placed upon the roof of a structure, the bars 29 and 30, together with the lower surface of clamp-ing flange 23, function as a tripod.

Referring now to the embodiment illustrated in Figures 8, 9 and 10, it will be observed that no fluid passes through the C clamp supporting bracket, generally designated by numeral 33, as

in the embodiment illustrated in Figures 1 to 7, inclusive, described hereinbefore. Instead, a tubular nozzle connector member 34 is secured in any suitable manner to the C clamp supporting bracket 33 such, for example, as by welding or by casting the member 34 integrally with the C clamp supporting bracket 33. The nozzle connector member 34 is provided with an externally threaded portion 35 at one end thereof for connecting the member 34 to a line of fire hose H. Nozzle 16 is mounted at the other end of the member 34 and a conventional valve 12 is disposed within the member 34 near the threaded end portion 35.

15 The C clamp supporting bracket 33 includes two portions 36 and 37, respectively. The portions 36 and 37 of the C clamp are provided with complementary halves of a double-sided hinge joint 38. When assembled portions 36 and 37 are connected to one another by bolts 39 and 41 which are inserted into registering holes provided in each side of hinge 38. By the provision of hinge 38, the two portions 36 and 37 of the C clamp supporting bracket may be folded one upon 20 the other for the purpose of conserving space during storage and providing an apparatus which may be easily transported from one position to another by a member of a fire fighting crew.

25 The pivotally mounted bars 42 and 43 are respectively provided with tubular end portions 44 and 45 for the accommodation of the shanks 46 and 47 of the pointed end portions 48 and 49. The length of the bars 42 and 43 may be adjusted to meet the particular conditions of operation by 30 merely extending or further inserting one or both of the shanks 46 and 47 within the tubular end portions 44 and 45 and then securing the shanks in their adjusted positions by means of pins 51 and 52 inserted into registering holes in each of 35 the tubular end portions 44 and 45 and in each of 40 the shanks 46 and 47.

45 Similarly, the tubular stop flange 53 receives the shank 54 of a capped rod 55 which is provided with a plurality of longitudinally spaced holes for registry with corresponding holes in stop flange 53 and is secured in a selected position by pin 56 passed through the registering holes in the stop flange and the shank.

50 Stated briefly in summary, the present invention contemplates the provision of a new and improved fire preventive apparatus which has a rotating nozzle associated therewith for the purpose of establishing a circular water curtain adjacent a structure desired to be protected from the heat of an adjacent fire.

55 The present invention has been described as being of a mobile type which may be temporarily clamped to a portion of a building or other structure. It will, of course, be apparent to those skilled in the art to which the present invention pertains that such an apparatus may be incorporated as part of the permanent fire preventive apparatus of the structure. Furthermore, it will be readily appreciated that different nozzles 60 having different operating characteristics may be utilized in accordance with the present invention without departing from the spirit thereof. In addition, under certain conditions of service, as when gasoline storage tanks are burning, it may be found desirable to apply a fluid other than water to the apparatus of the instant invention. The fluid chosen is, of course, dependent upon the nature of the fire and does not alter the inventive concept herein disclosed.

65 While the invention has been described with

reference to a certain preferred example, which gives satisfactory results, it will be understood that various changes and modifications may be made without departing from the spirit and scope of the invention, and it is my intention, therefore, to cover in the appended claims all such changes and modifications.

What is claimed as new and desired to be secured by Letters Patent of the United States is:

1. A fire preventing spraying apparatus including a support having an intermediate portion and angularly disposed end portions, a fluid nozzle connected to apparatus, said nozzle including a rotary cylindrical housing having circumferentially spaced discharge outlets located to rotatably drive the nozzle and to effect a circular water curtain disposed substantially parallel to a predetermined surface to be protected from fire, means for connecting the nozzle to a source of fluid under pressure, spaced coaxing clamping members connected to the end portions of said support for engaging a fixed member therebetween, to maintain the apparatus in a stationary position, and means pivotally connected to opposite sides of said intermediate portion for engaging a supporting surface.

2. A fire preventing spraying apparatus including a support having an intermediate tubular portion and angularly disposed end portions, one of said end portions being tubular and communicating with the intermediate tubular portion, a nozzle mounted on said tubular end portion, said nozzle including a rotatably cylindrical housing having circumferentially spaced discharge outlets at predetermined angles ranging from 0° to 10° relative to the center plane or diameter of the housing, means for connecting a source of fluid under pressure to the intermediate portion of the apparatus, valve means for controlling the supply of fluid to the apparatus, the end portions of said support having longitudinally aligned clamping members arranged to engage opposite sides of a fixed member to maintain the apparatus in a stationary position.

3. A fire preventing spraying apparatus including a support having an intermediate portion and angularly disposed end portions, said intermediate portion being in sections, means pivotally connecting said sections, a nozzle mounted on one

of the intermediate sections, said nozzle including a rotary cylindrical housing having circumferentially spaced discharge outlets, means for connecting a source of fluid under pressure to the nozzle, means for controlling the fluid supply to the nozzle, and adjustable clamping means connected to the end portions of the apparatus for engaging opposite sides of a fixed member to maintain the apparatus in a stationary position.

- 10 4. A fire preventing spraying apparatus including a support having an intermediate portion and angularly disposed end portions, said intermediate portion being in sections, means pivotally connecting said sections, a nozzle mounted on one of the intermediate sections, said nozzle including a rotary cylindrical housing having circumferentially spaced discharge outlets, certain of said outlets extending radially from the housing and others at inclined angles relative thereto so as to provide a protective circular water curtain between the apparatus and a predetermined surface to be protected from fire, means for connecting a source of fluid under pressure to the nozzle, means for controlling the fluid supply to the nozzle, adjustable clamping means connected to the end portions of the apparatus for engaging opposite sides of a fixed member to maintain the apparatus in a stationary position, and legs pivoted to opposite sides of the apparatus for 25 engaging the ground to assist in supporting the apparatus in operative position.
